UNITED STATES PATENT OFFICE.

ERNEST M. ORLOW, OF MILWAUKEE, WISCONSIN, ASSIGNOR OF ONE-HALF TO ARTHUR J. SCHMITT, OF MILWAUKEE, WISCONSIN.

GARMENT CONSTRUCTION.

Application filed November 15, 1924. Serial No. 750,140.

To all whom it may concern:

Be it known that I, ERNEST M. ORLOW, a citizen of the United States, and resident of Milwaukee, in the county of Milwaukee and 5 State of Wisconsin, have invented certain new and useful Improvements in Garment Constructions; and I do hereby declare that the following is a full, clear, and exact description thereof.

10 This invention relates to garment fly construction.

In constructing garments according to the previously known methods, it has been the practice to fold the edges of the facing 15 strip and of the body portion inwardly at its outer end as well as along the vertical edge. Thereafter a line of stitching has been run through these inwardly folded portions to furnish the vertical edge and bottom 20 edge of the fly. This necessarily placed the seam for the fly at the point where the greatest wear occurred and consequently the seam very quickly was destroyed or partly broken due to wear.

25 In addition to this the seamed edges would not produce the finish so much desired at this portion of garments.

This invention is designed to overcome the above noted defects, and objects of such invention are to provide a garment fly construction which does not have any vertical seamed edges, which has the end edges seamed or joined by a line of stitching spaced inwardly from the end edges of the 35 fly, and consequently neither exposed to view nor subjected to the large amount of wear as are the usual seams in flies.

Further objects are to provide a fly construction which avoids the bulky marginal 40 seam heretofore employed. It does not have any overlapping seams and is extremely flexible, which avoids curling, blistering or swelling, which is more economical in manufacture than the previously formed flies, and 45 in which provision is made for receiving the end of an inwardly folded portion of the body of the garment to thus provide an attractive finished appearance.

An embodiment of the invention is shown 50 in which the various stages in the manufacture of this fly are detailed.

In the drawings Figure 1 shows the blank as it appears when cut and laid out flat.

Figure 2 shows the next formation of the 55 fly construction.

Figure 3 shows the outer panel folded inwardly.

Figure 4 shows the finished fly as it appears from the inner side of the garment.

In illustrating this invention, the lower 60 end edge of a coat has been shown although it is to be understood that other ends and edges of flies of garments may be finished in this manner.

Referring to Figure 1 of the drawings, it 65 will be seen that the blank is in reality a continuation of the body portion 1 of the garment and comprises an intermediate panel 2 and an outer panel 3. The body portion is provided with a lower end edge 70 4 while the intermediate portion is provided with a lower end edge 5 which is spaced inwardly of the edge 4, as is apparent from Figure 1. The outer panel is similarly provided with a lower end edge 6 75 which is spaced inwardly of the end edge 5 of the intermediate panel. It is preferable in forming this blank to provide a curved V-shaped cut 7 at the junction of the edges 5 and 6. The next step in making the fly 80 is to provide a binding 8 for the end edges 5 and 6, as shown in Figure 2, and to provide a binding 9 for the vertical edge of the outer fly, and a binding 10 for the bottom edge of the body portion.

85 Figure 3 shows the manner in which the panels are related to each other when folded, and Figure 4 shows the finished fly. However, in the actual manufacture of the garment, the outer panel is folded over the intermediate panel as shown in Figure 3, but wrong side outwardly. The edges 5 and 6 are then overcast with a loose zig-zag stitch to form a line of stitching 12. Thereafter, the parts are folded right side outwardly, 90 the loose stitch acting as a hinge, and the seam is pressed flat as shown in Figure 4 with the edges 5 and 6 abutting.

95 It is to be noted that the outer panel 3 extends inwardly beyond the inner edging 100 of the intermediate panel 2 and overlaps a portion of the upwardly folded bottom edge of the body portion.

105 It is to be noted also that the overcasting 12 extends to the end of the outer panel 3 and thus securely holds such panel to the upwardly folded bottom portion 4 of the body portion.

If desired, a line of stitching 13 may join 110 the intermediate and outer panels and is

preferably spaced from the folded edge 11 of the finished fly to give a neat and attractive appearance. In addition to this, the vertical edge of the outer folded panel 3 5 may be blind stitched to the body portion 2.

It will thus be seen that a novel and extremely serviceable and effective fly construction has been provided for garments which may be most easily produced in a 10 cheap and rapid manner, which removes the seams from the edges of the flies and thus relieves the seams or lines of stitching from a large amount of wear which they heretofore had to stand.

15 It will further be seen that no vertical edge seam is employed, and that overlapping seams are avoided. This results in extreme flexibility and a very attractive and finished appearance.

20 Although the invention has been described in considerable detail, it is to be understood that the invention may be variously embodied and is, therefore, to be limited only as claimed.

25 I claim:

1. In a garment, a body portion, an intermediate panel having an end edge, an outer panel folded over said intermediate panel and having an end edge spaced inwardly 30 from the end edge of said intermediate panel, said end edge of the intermediate panel being folded inwardly into contact with the end edge of the folded outer panel, and a line of stitching joining the end edges 35 of said panels, said line of stitching being spaced inwardly from the end of the finished fly.

2. In a garment, a body portion, an intermediate panel having an end edge, an outer panel folded over said intermediate panel and having an inwardly spaced end edge, a binding enclosing the said end edges, and the end edge of the intermediate panel being folded inwardly into butting engagement with the end edge of said outer panel, and overcast stitching joining the butting 45 end edges of the said panels.

3. In a garment, a fly construction comprising an intermediate panel having its end stopping short of the end of the body portion, an outer panel folded over said intermediate panel with its end stopping short of the end of the intermediate panel, the end of the intermediate panel being folded over and stitched to the end of the outer panel, and the end of the body portion being folded inwardly and having a part positioned beneath a portion of the outer folded panel and stitched thereto.

4. In a garment, a fly construction comprising an intermediate panel having its end stopping short of the end of the body portion, an outer panel folded over said intermediate panel with its end stopping short of the end of the intermediate panel, the 65 end of the intermediate panel being folded over and stitched to the end of the outer panel by an overcast line of stitching, and the end of the body portion being folded inwardly and having a part positioned beneath 70 a portion of the outer folded panel and stitched thereto.

5. In a garment construction, the combination of a body portion, an intermediate panel projecting outwardly therefrom and having an end edge stopping short of the end edge of the said body portion, an outer panel folded over said intermediate panel and having an end edge stopping short of the end edge of the intermediate panel, a 75 binding enclosing the end edges of both panels, the end edge of said intermediate panel being folded inwardly in abutting relation with the end edge of the folded outer panel, overcast stitching joining the 80 abutting edges, said body portion having an outer end edge folded beneath a portion of the inwardly folded outer panel.

In testimony that I claim the foregoing I have hereunto set my hand at Milwaukee, in 90 the county of Milwaukee and State of Wisconsin.

ERNEST M. ORLOW.
